(57) **ABSTRACT**

The clip has a core and a sleeve. The sleeve encases the core. The clip is substantially rectangular in shape and has a first end and a second end. The clip is bendable into a shaped configuration. In the shaped configuration the first end of the clip is positioned next to the second end of the clip, the first end of the clip being substantially parallel to the second end of the clip, the first end of the clip and the second end of the clip defining an internal space between the first end of the clip and the second end of the clip. The clip is placed over the waist band of a user's pants to prevent portions of the waist band from rubbing on the underside of a user's shirt.

DEVICE AND METHOD FOR PROTECTING
CLOTHING

This application is a continuation of and claims priority to U.S. patent application Ser. No. 14/708,201 filed on May 9, 2015, which claims priority to U.S. provisional patent application Ser. No. 61/991,268 filed on May 9, 2015.

FIELD OF INVENTION

This invention pertains generally to clothing accessories and more particularly to a malleable device and method for protecting clothing.

BACKGROUND OF INVENTION

T-shirts have become a staple product in all wardrobes for men and women. T-shirts are as diverse as the millions who wear them and prices and fabrics vary. Some shirts are sold for upwards of \$500.00. Fabric used for t-shirts range from modal, blends of rayon/cotton/polyester and cotton. These fabrics are used because they have a sensual feel. Some t-shirts brands (especially high-end) have mastered the very thin, light weight, soft and comfortable fabric t-shirt that has become an imported item in high-fashion brand collections.

The most popular type of pants to wear are denim jeans. In contrast to the soft materials utilized for shirts, denim is a stiff and coarse material. Jeans normally have a pair of flaps surrounding the zipper with a button or a snap placed at top. Through movement and bending over, the corner of the front flap of the jeans bends outward. Because the most popular dress attire is the combination of t-shirt and jeans, the stiff, hardened corner of the jeans frequently comes into contact with the inside of the soft t-shirt. Over time, the continuous rubbing and movement of the corner of the jeans wears away the fabric of the t-shirt, causing a hole to appear in the lower front of the t-shirt. What is needed is a method and device to protect the t-shirt from the abrasion caused by the waistband of jeans at the button closure area.

SUMMARY OF INVENTION

The following presents a simplified summary in order to provide a basic understanding of some aspects of the disclosed innovation. This summary is not an extensive overview, and it is not intended to identify key/critical elements or to delineate the scope thereof. Its sole purpose is to present some concepts in a simplified form as a prelude to the more detailed description that is presented later.

A clip for adhering to clothing comprising a core and a sleeve. The core is an elongated rectangular body having a first end and a second end. The sleeve encases the core. The sleeve is composed of a soft and pliable material. The clip is substantially rectangular in shape and has a first end and a second end. The clip is bendable into a shaped configuration. In the shaped configuration the first end of the clip is positioned next to the second end of the clip, the first end of the clip being substantially parallel to the second end of the clip, the first end of the clip and the second end of the clip defining an internal space between the first end of the clip and the second end of the clip.

The core may be composed of a metal. The metal for the core is chosen from a group consisting essentially of: aluminum, steel, copper, nickel, gold, spring steel, tin, iron, silver, and zinc. The sleeve may be composed of a material

2

chosen from the group consisting essentially of: leather, rubber, synthetic rubber, sponge, synthetic sponge, silicone, polymer, and elastomer.

In another embodiment of the invention the core further comprises one or more core joints, the one or more core joints extending the width of the core, the one or more core joints being substantially perpendicular to the longitudinal axis of the core.

In another embodiment of the invention the sleeve further comprises one or more sleeve joints, the one or more sleeve joints extending the width of the sleeve and the one or more sleeve joints being substantially perpendicular to the longitudinal axis of the sleeve. In another embodiment of the invention the sleeve further comprises a textured region. The textured region may further comprise a tactile adhesive.

In another embodiment of the invention the core further comprises a first magnetized region and a second magnetized region. The first magnetized region is disposed toward the first end of the core. The second magnetized region is disposed toward the second end of the core. The first magnetized region is configured to exert an attractive force on the second magnetized region when the clip is bent into the shaped configuration.

In another embodiment of the invention the sleeve consists of two sleeve sections, the first sleeve section encasing the first end of the core, the second sleeve section encasing the second end of the core. In another embodiment of the invention the shaped configuration the clip is shaped to consist of a front member measuring 1.5 inches wide by 1.5 inches long, a rear member measuring 1.5 inches wide by 2 inches long, and an upper connector measuring 1.5 inches wide by $\frac{3}{8}$ inches deep from the outer point of the front member to the outer point of the rear member and $\frac{1}{4}$ inches deep from the inner point of the front member to the inner point of the rear member.

The invention is also directed toward method of preventing a section of the waist band of pants from rubbing against a shirt. The method comprises utilizing a clip in a first configuration, bending the clip into a second configuration, placing the clip over the waist band of a pair of pants, compressing the front member toward the rear member, and compressing the waist band of a pair of pants within the internal space between the front member and the rear member. The clip comprises a core and a sleeve. The sleeve encases the core. The sleeve is a soft and pliable material. The core is an elongate body having a first end and a second end. The clip is substantially rectangular in shape and has a first end and a second end. In the second configuration the first end of the clip is positioned next to the second end of the clip. The first end of the clip is substantially parallel to the second end of the clip and the first end of the clip and the second end of the clip define an internal space between the first end of the clip and the second end of the clip. When placed over the waist band of the pair of pants the first end of the clip is disposed between the waist band of a pair of pants and the shirt worn by the user, the second end of the clip is disposed between the waist band of a pair of pants and the user, and the waist band of the pair of pants is disposed within the internal space between the first end of the clip and the second end of the clip.

The method may further comprise lifting the first end of the clip away from the second end of the clip and removing the clip from the waist band of a pair of pants.

In another embodiment of the method the sleeve of the clip further comprises a textured area. In this embodiment the method further comprises ensuring the textured area is

disposed within the internal space between the front member and the rear member when the clip is in the second configuration.

In another embodiment of the method the core of the clip further comprises a first magnetized area disposed toward the first end of the core and a second magnetized area disposed toward the second end of the core with the first magnetized region being configured to exert an attractive force on the second magnetized region when the clip is bent into the second configuration. In this embodiment the method further comprises ensuring the first magnetized area is disposed adjacent to the second magnetized area when the clip is bent into the second configuration.

As it will be realized, the invention is capable of other different embodiments and its several details are capable of modifications in various obvious aspects all without departing from the scope of the invention. Accordingly, the drawing and descriptions will be regarded as illustrative in nature and not as restrictive.

BRIEF DESCRIPTION OF THE DRAWINGS

Various exemplary embodiments of this invention will be described in detail, wherein like reference numerals refer to identical or similar components, with reference to the following figures, wherein:

- FIG. 1 is a perspective view of the clip;
- FIG. 2 is a cross sectional view of the clip;
- FIG. 3A is a top view of the core;
- FIG. 3B is a perspective view of the core;
- FIG. 4A is a perspective view of the sleeve;
- FIG. 4B is a perspective view of the sleeve;
- FIG. 5 is a perspective view of the sleeve;
- FIG. 6 is a top view of an alternative embodiment of the core;
- FIG. 7 is a top view of the clip in a straightened configuration;
- FIG. 8 is a top view of an alternative embodiment of the clip in a straightened configuration;
- FIG. 9 is a front view of the clip;
- FIG. 10 is a side view of the clip; and
- FIG. 11 is a schematic describing the use of the clip.

DETAILED DESCRIPTION OF THE PREFERRED EMBODIMENT

The claimed subject matter is now described with reference to the drawings. In the following description, for purposes of explanation, numerous specific details are set forth in order to provide a thorough understanding of the claimed subject matter. It may be evident, however, that the claimed subject matter may be practiced with or without any combination of these specific details, without departing from the spirit and scope of this invention and the claims.

The invention is directed toward a clip for placing over the front button flap of a user's jeans to prevent the corner of the flap from wearing on a shirt worn by the user. Referring to FIG. 1, the clip 10 is displayed. The clip 10, when worn by the user, has a front member 12 and a rear member 16 connected by an upper connector 14. When worn by a user, the front member 12 is positioned on top of the button flap of the jeans. The upper connector 14 extends over the top edge of the button flap of the jeans and the rear member 16 extends behind the button flap of the jeans. The button flaps of the jeans are positioned in the space between the rear member 16 and front member 12 when worn by the user. When worn, the front member 12 is positioned between

the button flap of the jeans and the user's t-shirt. The front member 12 holds down the button flap and prevents the button flap of the jeans from rubbing on the t-shirt and causing wear.

The clip 10 is a thin elongated rectangular body. The clip 10 is malleable and bendable so that a user can angle and position the clip 10 in any desirable position. The user can also bend and angle the rear member 16 and front member 12 into any shape and position. The rear member 16 and front member 12 may be positioned relative to each other in any manner so that the upper connector 14 can be any length. The upper connector 14 may be positioned short in length so that the space between the rear member 16 and front member 12 is small and the clip 10 is tightly compressed onto the button flaps of the jeans. Alternatively the upper connector 14 may be positioned longer in length so that the space between the rear member 16 and front member 12 is greater and the clip 10 is loosely compressed onto the button flaps of the jeans.

Referring to FIG. 2, a cross section of the clip 10 is displayed. The clip comprises a core 100 and a sleeve 200. The core 100 is a thin elongate rectangular member. The core 100 may be made of any material. In the preferred embodiment the core 100 is composed of a malleable metal, such as aluminum, steel, copper, nickel, gold, spring steel, tin, iron, silver, zinc, or any other commercially available metal. The sleeve 200 is an elongate rectangular member with an internal cavity for holding the core 100. The sleeve 200 is composed of a soft and pliable material. Any type of material may be used for the sleeve 200. The sleeve 200 may be composed of leather, silicone, synthetic rubber, sponge, polymer, elastomer, or any other commercially available material.

Referring to FIG. 3A, the core 100 is displayed. When not in use the core 100 is an elongated rectangular member. Positioned approximately midway along the length of the core is a core joint 110. The core joint 110 extends along the width of the core 100 and substantially traverses the length of the core 100. The core joint 110 provides a point of flexibility such that the core 100 can be folded so that one end of the core 100 is disposed within the front member 12 and the opposite end of the core 100 is disposed within the rear member 16. The core joint 110 is disposed within the upper connector 14 when the core 100 is folded and in use. The core 100 may have one core joint 110 as displayed in FIG. 3A or may have two core joints 110a, 110b as illustrated in FIG. 3B. Between the first core joint 110a and the second core joint 110b is the upper core connector 112. The upper core connector 112 is disposed in the upper connector 14 when the clip 10 is in use. Each of the core joints 110a, 110b may be formed by a groove in the surface of the core 100. Alternatively, each of the core joints 110a, 110b may be formed by a depression or thinning of the thickness of the core 100. Alternatively, each of the core joints 110a, 110b may be formed by a hinge.

Referring to FIG. 4A and FIG. 4B the preferred embodiment of the sleeve 200 is displayed. The sleeve 200 has a sleeve back 202 and a sleeve front 204. The sleeve 200 has a first sleeve joint 210a and a second sleeve joint 210b. Positioned between the first sleeve joint 210a and a second sleeve joint 210b is the upper sleeve connector 212. The upper sleeve connector 212 is disposed in the upper connector 14 when the clip 10 is in use. The first sleeve joint 210a and a second sleeve joint 210b are respectively disposed adjacent to the first core joint 110a and the second core joint 110b. The upper sleeve connector 212 is disposed adjacent to the upper core connector 112. The sleeve joints

210a, 210b extend along the width of the sleeve **200** and substantially traverses the length of the sleeve **200**. The sleeve joints **210a, 210b** provide points of flexibility such that the sleeve **200** can be folded so that one end of the sleeve **200** is disposed within the front member **12** and the opposite end of the sleeve **200** is disposed within the rear member **16**.

Positioned on the sleeve front **204** is a textured region **206**. The textured region **206** is an area on the sleeve front **204** that provides an enhanced frictional surface to ensure the adhesion to the clip **10** to the button flaps of the jeans. The textured region **206** may be any size and shape. The textured region **206** may be formed by a dimpling in the material composing the sleeve **200**. Alternatively, the textured region **206** may be an additional pad of material adhered to the sleeve front **204**. The textured region **206** may be formed by a rigid polymer or rough type fabric. Alternatively, the textured region **206** may be a smooth area further comprising a tactile adhesive to removably secure the clip **10** to the button flap of the user's jeans.

Referring to FIG. 5 the sleeve **200** is displayed in a folded configuration as when it is in use. The sleeve back **202** is disposed on the external areas of the clip **10**. The sleeve front **204** is disposed on the areas of the clip **10** adjacent to the button flaps of the user's jeans. The textured region **206** is disposed on areas of the front member **12** and rear member **16** adjacent to the button flaps of the user's jeans. The first sleeve joint **210a** and second sleeve joint **210b** are positioned on the outer edges of the upper connector **14**. The upper sleeve connector **212** is coextensive with the upper connector **14**. The first sleeve joint **210a** is located at the joint between the upper connector **14** and rear member **16**. The second sleeve joint **210b** is located at the joint between the upper connector **14** and rear front member **12**.

Referring to FIG. 6, an alternative embodiment of the core is displayed. In the alternative embodiment the core **100** further comprises a first magnetized area **120** and a second magnetized area **122**. The first magnetized area **120** is disposed on one end of the core **100** and the second magnetized area **122** is disposed on the opposite end of the core **100** and are separated by the core joint **110**. The first magnetized area **120** has a magnetic charge opposite from the magnetic charge of the second magnetized area **122**. The first magnetized area **120** exerts an attractive force on the second magnetized area **122** through the button flaps of the jeans when the clip **10** is folded and being used. In this manner the first magnetized area **120** is disposed in the front member **12** and the second magnetized area is disposed in the rear member **16**. The attractive force between the first magnetized area **120** and the second magnetized area **122** draw the front member **12** and rear member **16** closer together, increasing the frictional hold of the clip **10** on the button flaps of the jeans and preventing the accidental removal of the clip **10**.

Alternative embodiments of the clip **10** are possible. As illustrated in FIG. 7, the core **100** may be fully encompassed by the sleeve **200**. Alternatively, as illustrated in FIG. 8, the core **100** may be encompassed on one end by a first sleeve section **200a** and the other end of the core **100** may be encompassed by a second sleeve section **200b**. In this embodiment the front member **12** is encased in the first sleeve section **200a** and the rear member **16** is encased in the second sleeve section **200b**. In this embodiment the upper connector **14** is composed solely of the core **100**.

The clip **10** may be configured to be any size and shape. The front member **12**, upper connector **14**, and rear member **16** may each be any size and shape. Referring to FIG. 9 and

FIG. 10 the preferred dimensions of the clip **10** are displayed. In the preferred embodiment the front member **12** is 1.5 inches wide and 1.5 inches long. The rear member **16** is 1.5 inches wide 2 inches long. The outer width of the upper connector **14** is $\frac{3}{8}$ inches. The internal width of the upper connector **14** is $\frac{1}{4}$ inches. The thickness of the clip **10** is $\frac{1}{16}$ inches.

Referring to FIG. 11 the method of utilizing the clip **10** is illustrated. First the user bends the clip into a curved shape **300**. Shaping the clip **10** into the curved structure substantially forms the front member **12**, upper connector **14**, and rear member **16**. The user places the clip over the button flaps of the jeans **302**. The user then compresses the front member **12** and rear member **14** together to adhere the clip to the button flaps of the jeans **304**.

Still other embodiments and methods of protecting clothing from rigid button flaps of jeans are conceivable. In one embodiment, the button flaps of the jeans are coated in a rigid material preventing distortion of the button flaps. For instance the button flaps may be dipped in a liquid polymer or elastomer which then dries and hardens into a stiff and unflexible sleeve. In other embodiments the clip can be sewn or otherwise adhered onto one of the two button flaps. The second button flap then fits within the internal space when the user buttons their pants. The user can then compress the front member and rear member together onto the two button flaps.

What has been described above includes examples of the claimed subject matter. It is, of course, not possible to describe every conceivable combination of components or methodologies for purposes of describing the claimed subject matter, but one of ordinary skill in the art can recognize that many further combinations and permutations of such matter are possible. Accordingly, the claimed subject matter is intended to embrace all such alterations, modifications and variations that fall within the spirit and scope of the appended claims. Furthermore, to the extent that the term "includes" is used in either the detailed description or the claims, such term is intended to be inclusive in a manner similar to the term "comprising" as "comprising" is interpreted when employed as a transitional word in a claim.

The invention claimed is:

1. A method of preventing a section of the waist band of pants from rubbing against a shirt comprising
  - a) utilizing a clip in a first configuration
    - i) said clip comprising
      - (1) a core, said core being an elongate body having a first end and a second end;
      - (2) one or more sleeve portions, wherein each of said one or more sleeve portions encase at least a portion of said core, each of said one or more sleeve portions being a soft and pliable material;
      - ii) wherein said clip is substantially rectangular in shape having a first end and a second end;
    - b) bending said clip into a second configuration
      - i) wherein in said second configuration said first end of said clip is positioned next to said second end of said clip, said first end of said clip being substantially parallel to said second end of said clip, said first end of said clip and said second end of said clip defining an internal space between said first end of said clip and said second end of said clip;
      - c) placing said clip over the waist band of a pair of pants
        - i) said first end of said clip being disposed between said waist band of a pair of pants and the shirt worn by the user;

- ii) said second end of said clip being disposed between said waist band of a pair of pants and the user;
  - iii) said waist band of said pair of pants being disposed within said internal space between said first end of said clip and said second end of said clip;
  - d) compressing said front member toward said rear member;
  - e) compressing said waist band of a pair of pants within said internal space between said front member and said rear member.
2. The method as in claim 1 further comprising
- a) lifting the first end of said clip away from said second end of said clip;
  - b) removing said clip from said waist band of a pair of pants.
3. The method as in claim 2
- a) wherein said one or more sleeve portions of said clip further comprises a textured area;
  - b) said method further comprising
- i) ensuring said textured area is disposed within said internal space between said front member and said rear member when said clip is in said second configuration.
4. The method as in claim 3
- a) wherein said core of said clip further comprises a first magnetized area disposed toward said first end of said core and a second magnetized area disposed toward said second end of said core, said first magnetized

5

10

15

20

25

region being configured to exert an attractive force on said second magnetized region when said clip is bent into said second configuration;

- b) the method further comprising

i) ensuring said first magnetized area is disposed adjacent to said second magnetized area when said clip is bent into said second configuration.

5. The method as in claim 1

a) wherein said one or more sleeve portions of said clip further comprises a textured area;

- b) said method further comprising

i) ensuring said textured area is disposed within said internal space between said front member and said rear member when said clip is in said second configuration.

6. The method as in claim 1

a) wherein said core of said clip further comprises a first magnetized area disposed toward said first end of said core and a second magnetized area disposed toward said second end of said core, said first magnetized region being configured to exert an attractive force on said second magnetized region when said clip is bent into said second configuration;

- b) the method further comprising

i) ensuring said first magnetized area is disposed adjacent to said second magnetized area when said clip is bent into said second configuration.
